SEMIPOWER PRESS AND TANDEM
CONTROL

Fred A. Heidenfelder, Chicago, Ill., assignor to
The American Laundry Machinery Company,
Norwood, Ohio, a corporation of Ohio

Application December 3, 1938, Serial No. 243,685

4 Claims.

(Cl. 38—5)

This invention relates to improvements in press operating and control mechanism both for the operation and control of a single pressing machine and for the joint or tandem operation of a plurality of pressing machines.

One of the objects of the present invention is to provide a pressing machine of the type which is first manually closed after which pressure is applied by power. One of the features of the invention is the specific arrangement of the means for holding the pressing head in pressing position and the specific arrangement of the parts for thereafter moving the pressing bed into engagement with the head.

Another object of the present invention is to provide means for holding a pressing head in pressing position and novel means for removing the head holding means from the position maintained during a pressing operation and operable automatically as the pressing power means is released.

Another object of the present invention is to provide means at one press operated in a novel manner by connection with one of the press parts as that press closes to actuate control means at another press to cause opening of that other press.

Another object of the present invention is to provide a tandem connection between a pair of pressing machines whereby one of them may be caused to open while the operator is at the other of the machines, together with novel means for selecting individual or tandem control as desired by the operator.

Other objects of the invention will appear from the accompanying drawings and specification and the essential features will be set forth in the claims.

In the drawings, Fig. 1 is an end elevation of a pressing machine embodying my invention, certain of the parts being shown in section or broken away to more clearly indicate the parts, the control mechanism being here shown diagrammatically and the full line position of the parts corresponds to open position of the press while the dot-dash position indicates a safely closed condition of the press; Fig. 2 is a view similar to Fig. 1 but showing the press fully closed; Fig. 3 is an enlarged fragmental detail of the head maintaining strut releasing and control mechanism, certain of the parts being shown in section; Fig. 4 is a sectional view taken along the line 4—4 of Fig. 1; while Fig. 5 is a diagrammatic view of control mechanism showing a tandem control

connection of two pressing machines similar to those shown in Figs. 1 to 4.

In the pressing machine illustrated, a frame 10 includes a pair of mutually facing vertical channels 10a at the rear portion thereof between which is carried a pivot 11 upon which is mounted a head lever 12. This lever carries at its forward end a pressing head 13 which is movable from the open position shown in full lines in Fig. 10 to a safe closed or pressing position indicated in dot-dash lines thereto. For the purposes of this invention the pressing head is moved to pressing position manually by the operator grasping the handle 14. Means is provided for holding 15 the head in its pressing position while pressure is applied from below. This means comprises a strut 15 pivotally mounted on the rear end of the head lever at 16. The strut has a bifurcated lower end which carries a pin 15a which in turn 20 rides along tracks 17 secured to the rear flanges of the channels 10a. At the upper ends of these tracks are abutments 17a against which the pins 15a may lodge so as to prevent downward movement of the strut. Cushioning bumpers 18 are 25 provided to lessen the noise as the pins engage the shoulders. Means is provided for urging the lower end of the strut 15 toward the shoulders or abutments 17a and in the embodiment here shown this is combined with means for urging 30 the head 13 to its open position. To this end a spring 19 is connected between the frame and a rearwardly extending bracket 15b on the strut 15. Thus the spring not only urges the head lever to open position but because of its offset 35 relation to pivot 16 urges the pins 15a against tracks 17 so that upon reaching the proper position they lodge on the shoulders or abutments 17a. A snubbing device for the head lever action is indicated at 20.

40 The pressing bed 21 is mounted in a bracket 22 of the frame for limited vertical movement. This movement is guided by pins 23 and the bed is urged downwardly by springs 24. A pressure pin 25 extends downwardly below the bed where 45 it is engaged by the shorter arm 26a of a bell crank 26 which is pivotally mounted in the frame. The longer arm of the bell crank 26b is pivotally connected at its lower end with the piston rod 27a of the cylinder and piston motor 50 27. The cylinder 27b of this motor is pivotally mounted in the frame at 28. A spring 29 urges the bell crank 26 in a clockwise direction as viewed in Figs. 1 and 2. Motive fluid is supplied to the motor 27 by way of a combined flow and 55 exhaust conduit 30 which communicates with a

fluid supply at 31 by way of a valve casing 32. This casing houses an inlet valve 32a urged toward closed position by the spring 32b. Conduit 30 is connected with exhaust through valve casing 33 which houses a valve 33a urged toward closed position by the spring 33b. Pivotaly mounted on the frame between these valves is a manually operated lever 34 having a pair of rigid cam arms 34a and 34b. These cam arms have substantially flat end portions adapted to engage against fingers 35a and 35b respectively, to push against valve stems 32c and 33c respectively, to urge valves 32a and 33a to open position. The arrangement of the parts is such that when manual 34 is in the position shown in Fig. 1 the inlet valve is closed and the outlet valve is held open, while in the position of the manual 34 shown in Fig. 2 the reverse condition occurs corresponding to closed position of the press. It will be noted that because of the arrangement of the valve springs and the flat end portions of the cam arms, the manual 34 will hold the valves in either of the positions of Figs. 1 and 2, upon the mere placing of the manual in the corresponding position.

Both manual and automatic means are provided for moving the strut 15 out of its head maintaining position shown in Fig. 2 at the close of a pressing operation. The manual control comprises a rod 36 mounted for reciprocal movement in the frame and having its rear end 36a located adjacent the strut 15. A spring 36b urges this rod to inoperative position. Obviously, pushing the rod rearwardly will dislodge the strut 15 from the shoulders 17a. The automatic means comprises a servomotor 37 suitably mounted on the frame and having a piston 37a whose piston rod 37b is located adjacent the lower end of strut 15 when the strut is in head maintaining position. A spring 37c urges the piston 37a to inoperative position in its cylinder. Motive fluid is supplied to servomotor 37 through conduit 38, valve casing 39 and conduit 40 which communicates with the source 31. The valve casing 39 is one of two valve casings which are mounted side by side on a bracket 41 which is secured to the frame. The other valve casing is for tandem operation and will be later described. Casing 39 houses a normally closed valve 39a whose stem 39b is engaged by a finger 42. Pivotaly connected with bell crank 26 is a bar 43 which carries a cam finger 44 which as shown in Fig. 3 rotates freely in a clockwise direction as bar 43 moves forward while bell crank 26 is moving in a pressure producing direction. The cam finger however is held by a stop 44a against counterclockwise movement when bar 43 moves rearwardly as the bell crank 26 moves in pressure releasing direction. Therefore when pressure has been relieved from the pressing bed bar 43 moves rearwardly and the cam finger 44 wipes over the finger 42 thus momentarily opening the valve 39a and sending a shot of air to servomotor 37 to remove the strut 15 from its head holding position. To insure proper travel of the bar 43 it is confined beneath a roller 45 suitably supported in the bracket 41. The piston 37a may be made a loose fit in its cylinder so that after it has made a power stroke it is quickly returned to inoperative position by the spring 37c as soon as valve 39a closes.

In the tandem control connection means is provided for returning the manually operated lever 34 of one machine to press opening producing position upon movement of the bell crank 26

of the other machine in pressure producing direction. As is well understood the purpose of such a control is to enable an operator to efficiently work two machines at one time. As the operator closes one machine the tandem connection will automatically open the other machine so that it is ready to work on as soon as reached. The arrangement here shown comprises a servomotor 46 located one at each machine with a piston rod 46a adapted upon a power stroke of the servomotor to move the manual 34 from the position of Fig. 2 to that of Fig. 1 so as to permit the press to open. The supply for this servomotor is by way of conduit 47 extending to the other machine and communicating through valve casing 48 with a pressure fluid supply 49. Each valve casing 48 as best seen in Fig. 5 houses a normally closed inlet valve 48a having a stem 48b engaged by a finger 50. Manual 51 has a cam arm 51a with a flattened end portion so that when the manual is moved to open valve 48a the parts will stay put in that position. When tandem control is desired the manuals 51 will be in the full line position of Fig. 5 whereas when tandem control is not desired these manuals will be moved to the dot-dash position of Fig. 5 to close the valves 48a. Thus whether or not there is flow through conduit 47 will depend upon the position of manual 51. The piston of servomotor 46 may be made a loose fit in its cylinder so that the spring returns the servomotor to inoperative position as soon as the fluid supply is cut off.

Means is provided for automatically supplying pressure fluid through the conduit 47 to servomotor 46 upon a press closing operation of the other press. Referring to Figs. 4 and 5, on the side of bar 43 opposite to that which carries the cam finger 44 is mounted another cam finger 52. For purposes of the diagram in Fig. 5 a fragment of the bar 43 is shown in the upper position so as to more clearly disclose the operative arrangement of the parts.

The supply of pressure fluid to servomotor 46 at one press through conduit 47, valve casing 48 and conduit 49 is by way of a valve casing 53 located at the other press alongside of the valve casing 39 and supported by the same bracket. This casing houses a normally closed valve 53a whose stem 53b is engaged by a finger 54. Referring to Fig. 5 it will be noted that the cam finger 52 rotates freely in a counterclockwise direction as bar 43 moves rearwardly but is held against turning by stop 52a when bar 43 moves forwardly. This forward movement of bar 43 corresponds to pressure producing movement of bell crank 26 so that as press A shown to the left in Fig. 5 closes, the cam finger 52 momentarily depresses the valve stem 53b providing a shot of air from the source 55 through conduits 49 and 47 to the servomotor 46 of the other press to there cause a press opening operation.

The operation of this tandem connection will now be apparent from Fig. 5 where press A at the left of the diagram is indicated in open position and press B at the right of the diagram is shown in closed position. The manual 34 of press B is maintaining fluid supply to the power motor 27 of that press. As the operator moves manual 34 of press A to the dot-dash position to cause a flow of fluid to motor 27 of press A, the bell crank 26 of press A will move in a counterclockwise direction causing bar 43 to move forwardly. Cam finger 52 will momentarily open the valve 53a, sending air through conduits 55 and 49, valve casing 48 and conduit 47 to servo-

motor 46 of press B. This motor will make an upward stroke engaging the cam arm 34a and moving the manual 34 in a counterclockwise direction so as to permit valve 32a of press B to close and opening exhaust valve 33a of press B. This will exhaust the motor 27 of press B permitting the spring 19 of that press to open it. As press B opens the cam finger 44 will momentarily send a shot of air to the servomotor 37 of press B to remove its strut 15 from the shoulders 17a so that the head may be raised to open position.

It will be noted that I have provided a very simple tandem control requiring no thought on the part of the operator except that required to position the manual 51 in its lower position if tandem operation is desired or in its upper position if tandem operation is not desired. This manual 51 will stay in either position in which it is placed and thus renders the selection of individual or tandem operation very easy.

What I claim is:

1. Control means for coordinating single-operator control of a pair of pressing machines each having coating pressing elements, having power actuated operating mechanism for causing relative closing and opening movements of said elements, and each press having control means for said operating mechanism for causing press closing and opening operations of each press by itself, comprising a servomotor for actuating said control means at one pressing machine in a direction to cause opening of that one machine, a fluid supply for said servomotor including a valve adapted to remain in either open or closed position when once placed in that position and a normally closed valve, and means for opening said last named valve by press closing operation of the other pressing machine, whereby an operator standing at said other machine may there cause press closing operation of that press, whereupon the remote press will automatically open.

2. Control means for coordinating single-operator control of a pair of pressing machines each having a frame supporting a pressing head, having means for holding said head in pressing position, having a pressing bed vertically movable in said frame into engagement with said head and a lever having an operative connection with said bed for raising it into engagement with said head, and having a fluid motor operatively connected with said lever for causing movement of said bed into and out of pressure engagement, comprising control means for causing out-of-engagement movement of said motor including a servomotor at one machine, a fluid supply for said servomotor including a normally closed valve at the other machine, and means for opening said valve by movement of the lever of said other machine in pressure producing direction.
3. Control means as in claim 2 wherein said last named means comprises a bar connected with said lever of said other machine, and a cam carried by said bar and adapted to open said valve by pressure producing movement of said lever.
4. Control means for coordinating single-operator control of a pair of pressing machines each having coating pressing elements and operating mechanism for causing relative closing and opening movements of said elements, each press having control means for causing press closing and opening operations including a fluid motor and a valve arranged to remain in either fluid supply or cut-off position when so positioned, each press having a servomotor for moving said control means from supply to cut-off position, and a fluid supply for said servomotor of one press including a valve adapted to remain either open or closed when so positioned and a normally closed valve, and means for opening said last named valve momentarily by press closing operation of the other pressing machine.

FRED A. HEIDENFELDER.
